UNITED STATES PATENT OFFICE.

REUBEN HALEY, OF BEAVER, PENNSYLVANIA, ASSIGNOR TO UNITED STATES GLASS COMPANY, OF PITTSBURGH, PENNSYLVANIA, A CORPORATION OF PENNSYLVANIA.

DESIGN FOR A GLASS CASSEROLE OR BAKING-DISH AND COVER.

54,914.

Specification for Design.

Patented Apr. 20, 1920.

Application filed October 6, 1919. Serial No. 328,919. Term of patent 7 years.

To all whom it may concern:

Be it known that I, REUBEN HALEY, a citizen of the United States, and residing at Beaver, in the county of Beaver and State of Pennsylvania, have invented a certain new, original, and ornamental Design for a Glass Casserole or Baking-Dish and Cover, of which the following is a specification, reference being had to the drawings forming a part thereof, wherein—

Figure 1 is a top view of the dish and Fig. 2 is a view in elevation of the same.

The dish consists of a body portion 3 and a cover 4.

I claim:

The ornamental design for a glass casserole or baking dish and cover, substantially as shown.

REUBEN HALEY.
